[57] **CLAIM**

The ornamental design for a footed oval bowl, substantially as shown and described.

DESCRIPTION

FIG. 1 is a side elevational view of a footed oval bowl embodying our new design.

FIG. 2 is a top plan view thereof.

FIG. 3 is a vertical sectional view taken along line 3—3 of FIG. 2.

FIG. 4 is a vertical sectional view taken along line 4—4 of FIG. 2.

FIG. 5 is a horizontal sectional view taken along line 5—5 of FIG. 3.

The surface ornamentation shown in FIG. 1 is continuous around the entire periphery of the bowl.

FIG. 1

FIG. 2
